UNITED STATES PATENT OFFICE.

WILLIAM B. NORTH, OF LUMBERTON, NORTH CAROLINA.

TUG-LOOP.

1,138,776.

Specification of Letters Patent.

Patented May 11, 1915.

Application filed September 15, 1914. Serial No. 861,823.

To all whom it may concern:

Be it known that I, WILLIAM B. NORTH, a citizen of the United States, residing at Lumberton, in the county of Robeson and 5 State of North Carolina, have invented certain new and useful Improvements in Tug-Loops, of which the following is a specification, reference being had to the accompanying drawings.

10 This invention relates to an improved tug loop for supporting vehicle shafts or poles and has for its primary object to provide a device of this character, whereby the shaft will be properly supported but which admits of easy and quick removal of the shaft from the loop.

The invention has for a more particular object to provide an elongated metal loop provided in one side with a pivotally mounted 20 spring held latch element through the medium of which the loop may be opened for the insertion of the shaft or pole, and improved means for connecting the loop to the tug strap of the harness.

25 The invention has for a further general object to improve and simplify devices of the above character, whereby the same are rendered strong and durable as well as highly convenient and serviceable in practical use.

With the above and other objects in view, the invention consists in novel features of construction, combination and arrangement of parts as will be hereinafter referred to 35 and more particularly pointed out in the specification and claim.

For a full understanding of the invention, reference is to be had to the following description and accompanying drawing, in 40 which:

Figure 1 is a side elevation, partly in section, showing a tug loop constructed in accordance with the preferred embodiment of my invention, Fig. 2 is a view looking at 45 right angles to Fig. 1, certain parts of the loop being shown in section.

Referring in detail to the drawing 5 designates generally an elongated metal loop. The space between the opposed side portions 50 of this metal loop is of greater width at one end of the loop than at the other end thereof, as clearly shown at 6 in Fig. 2 of the drawing. One of the side bars of the loop between these wide and narrow end portions 55 is inwardly bent or curved, as at 7, for a

purpose which will be later referred to. The opposed side bar of the tug loop immediately opposite to the bend 7 is cut out or gapped to provide an entrance opening or throat. This entrance opening in the loop 60 bar is normally closed by means of a latch plate 8, which is pivotally mounted at one of its ends in suitable bearing sleeves 9, formed upon the loop bar at one end of the entrance opening.

10 designates a length of spring wire 65 which is coiled upon the pivotally mounted end of the latch plate 8 and has one of its extremities 11 engaged upon the inner face of the loop bar, while the other extremity 12 70 of said spring has bearing engagement upon the corresponding face of the latch plate 8. This plate is formed with an extension, or inwardly projecting enlargement 13, which in conjunction with the inwardly curved 75 portion 7 of the loop bar restricts the space between the opposite sides of the loop, as indicated at 14. The free end of the latch plate 8 is adapted to engage against a stop rib 15, formed upon the end of the loop bar. 80 The latch plate preferably tapers longitudinally from its pivoted to its free end, and is provided adjacent to its pivoted end with finger receiving recesses or depressions 16.

As clearly shown in Fig. 2 of the drawings, the tug loop is provided in its inner face and at its wider end with a groove or recess 17. This recess receives a sleeve 18, which is loosely engaged upon one of the parallel portions of a loop rod 19 to which 90 one end of the belly band 20 of the harness is adapted to be connected. The shaft or pole 21 is arranged within this wider end of the tug loop 5 and bears upon the sleeve 18 to retain the same within the groove 17. 95 The tug loop is connected to the tug strap, which is attached to the back band of the harness in the usual manner by means of a buckle 22. This buckle includes a rectangular metal frame having one of its ends angularly extended, as shown at 23. Between the opposite sides of the buckle frame at the juncture of the body portion thereof with the extension 23, a tongue 24 is pivotally mounted. This buckle is assembled upon 100 the tug loop by engaging the latch plate 8 through the extended portion 23 of the buckle frame between the same and the tongue 24, and then sliding the buckle longitudinally over the latch plate and upon the 105 tongue 24. 110

narrower end of the tug loop. At this end of the metal loop the same is provided with an opening 25, through which the tongue 24 is adapted to be projected. The tug strap 5 26 is inserted through the buckle frame, the tongue 24 being engaged in an opening in the strap, and the extremity of said strap disposed between the intermediate portion of the extension 23 of the buckle and the 10 opposed portion of the tug loop.

From the foregoing description taken in connection with the accompanying drawings, it is thought that the construction and manner of use of my invention will be 15 clearly and fully understood. When the pole or shaft 21 is arranged within the lower end of the tug loop, said loop is securely closed by the latch plate 8, and the inwardly projecting enlargement 13 of said 20 loop together with the inwardly curved portion 7 of the loop bar precludes the possibility of the pole rising above this point, and thus obviates all liability of the pole bearing against the connecting buckle 22 25 and releasing the tongue thereof from connection with the tug strap. The pole or shaft may be very easily and quickly removed from the loop by simply engaging the thumb and forefinger of the hand in the 30 recesses 16 of the latch plate, and forcing said plate inwardly until its free end engages with the opposite side of the loop. The pole may then be lifted and moved outwardly through the entrance opening or 35 throat of the tug loop. It will thus be seen that I have produced a highly serviceable and convenient tug loop, which will at all times properly support the shaft or pole and obviate the possibility of its accidental release. The loop may be very easily and 40 quickly detached from the tug strap when

necessary, and is readily connected thereto by means of my improved buckle.

Owing to the very few parts employed in the construction of the invention it will be 45 appreciated that the device is extremely strong and durable in practical use and may be manufactured at comparatively small cost.

While I have described the preferred 50 form, construction and arrangement of the several elements employed, it will be understood that the device is, nevertheless, susceptible of considerable modification therein, and I therefore reserve the privilege of 55 resorting to all such legitimate changes as may be fairly embodied within the spirit and scope of the invention as claimed.

What I claim is:

A shaft supporting tug comprising an 60 elongated metal loop having an entrance opening in one side thereof and adjacent to one of its ends, and an inwardly opening spring held latch plate normally closing said entrance opening, said latch plate being formed with an enlargement to limit the movement of the shaft with respect to the loop in one direction, and said loop being provided with an opening in one of its ends, in combination with an attaching buckle including a frame adapted to receive the loop, and a tongue pivotally mounted in said frame to extend through the opening in the end of the tug loop for connection to the 65 70 75 tug strap.

In testimony whereof I hereunto affix my signature in the presence of two witnesses.

WILLIAM B. NORTH.
